UNITED STATES PATENT OFFICE.

JAMES S. REID, OF CLEVELAND, OHIO, ASSIGNOR TO THE EASY-ON CAP COMPANY, OF CLEVELAND, OHIO, A CORPORATION OF OHIO.

CAP CLOSURE.

Application filed March 3, 1922. Serial No. 540,749.

This invention relates to improvements in closures for automobile gasoline tanks and the like.

The objects of the invention are to provide an improved closure for automobile gasoline tanks, automobile radiators and the like, together with means for providing a baffled air vent through said closure; to provide such a closure with spring fingers for locking engagement with a part of the container, together with means for bracing said fingers and for distributing the strain at the base of the fingers; and to provide such a closure which can be manufactured at the least possible cost and which at the same time will prove extremely efficient in its security as a closure and in the reduction of strain and wear upon the parts.

Further objects of the invention are in part obvious and in part will appear more in detail hereinafter.

In the drawings, Fig. 1 is a plan view of my improved closure; Fig. 2 is a section on line 2—2, Fig. 1; Fig. 3 is a section on line 3—3, Fig. 1; Fig. 4 is an inverted plan view of my closure; Fig. 5 is a plan view of the tubular member to which the closure is applied; and Fig. 6 is a section on line 6—6, Fig. 5.

The tubular member 1, which may be formed integrally with the container or suitably secured as a separate part thereto, is provided at its upper end with the inwardly extending flange portion 2 and the downwardly extending flange portions 3, the last named flange portions being separated by the recesses 4. The lower edges of the flanges 3 are inclined so as to form cam faces for engagement by the locking member of the closure, as will later appear, and are provided also with the lugs 6 to serve as stops for limiting the rotary movement of the closure thereupon.

The closure comprises a body member having a depending flange 7 which is adapted to engage about the tubular member 1 and is provided with the annular gasket 8 of cork or other suitable material which engages the top portion of member 1 so as to seal the opening thereof. The top portion 9 of the closure body member is provided with a central dome 10, and a spring locking member with a substantially circular body portion 11 is secured to the closure body member by crimping the base portion of the

dome 10 about the edge of the body portion 11 of the spring locking member. The crimping does not extend completely around said body portion, but free air passages are permitted around the base of the locking fingers 60 12 of the locking member so as to afford communication between the inside of the closure and the chamber 13 in the dome portion 10, as will later appear. An opening 14 is provided in the top of the dome 10 for 65 establishing communication between chamber 13 and the outside atmosphere. The fingers 12 extend outwardly and downwardly and terminate in the angular portions 15 which are curved transversely so as to provide a substantially point contact with the cam edges of the downwardly extending flanges 3, as indicated in Figs. 2 and 3. Channels or ducts 16 are provided in the closure body member in the region of connection of the base and finger portions of the locking member, thereby providing a means of communication between the inside of the closure and the chamber 13 thereof. As thus far described this structure is substantially the same as that disclosed in my co-pending application, Serial No. 524,396, filed December 23, 1921, to which reference may be had for a more complete understanding of the same. 75

In the present improved structure I have struck up the sheared portions 17 at the base of the locking fingers 12, thereby providing openings through the spring locking member at the base of the fingers 12 thereof, 80 and at the same time utilizing the sheared portions as a baffle means for the openings to prevent the splashing of gasoline or other contents therethrough. These sheared portions serve also as a means of bracing the 85 finger portions 12 at the junction of the finger portions and the body portion 11 of the spring locking member. Therefore, the strain at the junction of the finger and base portions of the locking member is, as a result of the present structure, so distributed 90 that the danger of the finger portions 12 tearing from the spring locking member is minimized.

In order to apply the present closure to 105 the tubular member 1, the spring fingers 12 are inserted through the recesses 4 of said members and rotary motion is imparted to the closure so as to cause the finger end portions 15 to ride up the cam edges until the 110

- closure has been secured to the tubular member 1 with sufficiently tight interlocking engagement. As explained in the companion application before referred to, the 5 gasket is relieved of the grinding action which might otherwise be caused by the rotary movement of the closure, by virtue of the yielding of the spring fingers as they ride up the cam edges of the flanges 3.
- 10 It is to be understood that in the present structure, the vents 16 may or may not be used in connection with the vents provided by the sheared portions 17, and it is to be understood also that dwell portions 18 may 15 be provided in the cam edges of the flanges 3 so as to receive the finger end portions 15 and maintain them in such position.

With the present structure I am enabled to increase the air vent when employed in conjunction with the original air vent 16, and at the same time protect the original vent against the accidental escape of the gasoline or other contents. Furthermore, by bracing the spring fingers and distributing the strain 25 at the junction of the spring fingers and the body portion 11 of the spring locking member, I am enabled to employ either bronze or brass for such spring locking member which means a decided saving in the cost of the 30 material for this part of the device.

What I claim is:—

1. A closure, comprising a closure body, a locking member carried thereby and including a body portion and a resilient finger portion extending out of the plane of the body portion, and re-enforcing means effective at the junction of said finger portion and said body portion.
2. A closure, comprising a closure body, a locking member carried thereby and including a body portion and a finger portion extending out of the plane of the body portion, and a reenforcing web integral with the locking member and effective at the junction 45 of the finger portion and the body portion thereof.
3. A closure, comprising a closure body, a locking member carried thereby and including a body portion and a finger portion extending out of the plane of the body portion, and a reenforcing web connecting said finger and body portions and effective at the junction thereof.
4. A closure, comprising a closure body, and a locking member carried thereby, said closure body and said locking member being spaced so as to form an air chamber therebetween, said locking member being provided with a baffled opening providing communication 55 between the inside of the closure and said air chamber, and said air chamber having a vent opening to the outside atmosphere.
5. A closure, comprising a body member, a locking member carried thereby, said body

and locking members being spaced so as to form an air chamber therebetween, said body member being provided with a circuitous air passage leading from the inside of the closure to said air chamber, said locking member being provided with a baffled vent there-through, and said chamber having a vent opening to the outside atmosphere. 70

6. A closure device comprising a tubular member and a cap member, one of said members having spaced recesses and cam portions, the other member being provided with a locking member including a body portion and finger portions, said finger portions being adapted to enter said recesses and engage 80 said cam portions upon relative rotation of said cap and tubular members, said cap and locking members being spaced so as to form an air chamber, said cap member being provided with a circuitous air passage leading 85 from the inside thereof to said chamber, said locking member having a portion sheared at the base of one of said finger portions and extending inwardly so as to form a baffled opening therethrough and in communication 90 with said first air passage.

7. A closure device comprising a tubular member and a cap member, one of said members having spaced recesses and cam portions, the other member being provided with a locking member including a body portion and finger portions, said finger portions being adapted to enter said recesses and engage 100 said cam portions upon relative rotation of said cap and tubular members, said cap and locking members being spaced so as to form an air chamber, said locking member having a portion sheared at the base of one of said finger portions and extending inwardly so as to form a baffled opening leading 105 from the inside of the cap to said air chamber, and said chamber having a vent opening to the outside atmosphere.

8. A closure device comprising a tubular member and a cap member, one of said members having spaced recesses and cam portions, the other member being provided with a locking member including a body portion and finger portions, said finger portions being adapted to enter said recesses and engage 110 said cam portions upon relative rotation of said cap and tubular members, said cap and locking members being spaced so as to form an air chamber, said locking member having a portion sheared along its two sides at the base of one of said finger portions and extending inwardly so as to form a baffled opening leading from the inside of the cap to said chamber, and said sheared portion being so formed as to also provide a 115 bracing means for said finger portion.

9. As a new article of manufacture, a cap having a peripheral guide flange, and a metal plate secured within said cap by crimping or bending the material of the lat- 130

ter around the edge of said plate, said plate having a pair of legs or extensions projecting from opposite sides thereof, the material being slotted between the body of the plate 5 and the ends of the legs connected thereto.

10. A closure, comprising a closure body member, a locking member carried thereby and provided with a body portion and a resilient finger portion, said closure body member and said locking member having separated portions providing an air chamber therebetween, and means at the junction of the body and finger portions of said locking member for bracing said finger portion, 15 said means also providing an air vent between the inside of the closure and the air chamber thereof, and said chamber also having a vent opening to the atmosphere.
11. A closure, comprising a closure body member, a locking member carried thereby and provided with a body portion and a resilient finger portion, said closure body member and said locking member having separated portions providing an air chamber 20 therebetween, and means at the junction of the body and finger portions of said locking member for bracing said finger portion, said means also providing a baffled air vent between the inside of the closure and the air 25 chamber thereof, and said chamber also having a vent opening to the atmosphere.
12. A closure, comprising a closure body member, a locking member carried thereby and provided with a body portion and a 30 resilient finger portion, said closure body

member and said locking member having separated portions providing an air chamber therebetween, and means at the junction of the body and finger portions of said locking member and integral with said locking 40 member for bracing said finger portion, said means also providing an air vent between the inside of the closure and the air chamber thereof, and said chamber also having a vent opening to the atmosphere. 45

13. A closure, comprising a closure body member, a locking member carried thereby and provided with a body portion and a resilient finger portion, said closure body member and said locking member having separated portions providing an air chamber 50 therebetween, and a web at the junction of the body and finger portions of said locking member and integral with said locking member for bracing said finger portion, said web also providing a baffled air vent between the inside of the closure and the air chamber thereof, and said chamber also having a vent opening to the atmosphere. 55

14. A closure, comprising a closure body member, a locking member carried thereby and provided with a body portion and a resilient finger portion, and means at the junction of the body and finger portions of 60 said locking member for bracing said finger portion. 65

In testimony whereof I hereby affix my signature.

JAMES S. REID.
